UNITED STATES PATENT OFFICE.

ROSS M. G. PHILLIPS, OF WEST HAVEN, CONNECTICUT, ASSIGNOR TO THE AUTOMATIC STOVE CO., OF MINNEAPOLIS, MINNESOTA, A CORPORATION.

COOKING APPARATUS.

1,105,532.

Specification of Letters Patent. Patented July 28, 1914.

Application filed May 7, 1914. Serial No. 838,952.

To all whom it may concern:

Be it known that I, Ross M. G. PHILLIPS, a citizen of the United States, residing at West Haven, in the county of New Haven 5 and State of Connecticut, have invented a new and useful Improvement in Cooking Apparatus; and I do hereby declare the following, when taken in connection with the accompanying drawings and the characters 10 of reference marked thereon, to be a full, clear, and exact description of the same, and which said drawings constitute part of this application, and represent, in—

Figure 1 a view in front elevation of a 15 liquid fuel vapor-burning cooking apparatus constructed in accordance with my invention. Fig. 2 a view on a larger scale of the apparatus in vertical central section on the line *a*—*b* of Fig. 1, showing the legs of the 20 casing broken away. Fig. 3 a view in transverse vertical section looking from rear to front, with the food-container removed and with the legs of the casing broken away. Fig. 4 a broken detail view in horizontal 25 section on the line *c*—*d* of Fig. 3. Fig. 5 a detached plan view on a larger scale of the laterally movable preheater-carrier of the apparatus. Fig. 6 a detached view of the preheater-carrier in vertical longitudinal 30 section. Fig. 7 a detached view of the preheater-carrier in front elevation. Fig. 8 a view thereof in vertical section on the line *c*—*f* of Fig. 5. Fig. 9 a detached view in vertical section of the visual fuel-level indicator. Fig. 10 a similar view of the air-release valve. Fig. 11 a detached broken plan view of the preheater-bowl stripped of all 35 burner fittings. Fig. 12 a detached perspective view of the bridge of the visual fuel-level indicator.

My invention relates to an improvement in a cooking apparatus of the type shown and described in my pending application filed July 20, 1912, Serial No. 710,630, in 45 which a food-container having ingress and egress draft-passages, is used in conjunction with a preheater adapted to act as a closure for the ingress draft-passage and in which the said food-container and preheater are 50 normally spaced apart by spacing mechanism the releasing function of which is automatically controlled.

The object of my present invention is to

construct a liquid fuel vapor-burning apparatus of the type described. 55

With these ends in view, my invention consists in a liquid fuel vapor-burning cooking apparatus having certain details of construction and combinations of parts as will be hereinafter described and pointed out in 60 the claims.

Since my present invention relates primarily to different features of a sliding pre-heater-carrier, I will describe the different parts thereof before describing the other features of the typical apparatus. 65

In carrying out my invention, I employ a shallow sheet-metal tray 2 having longitudinal side flanges 3 which fit into two parallel guide-ways 4 secured to the bottom of 70 the casing 6 which is supported upon legs 7. The front wall of the said casing 6 is formed at its lower edge with a large rectangular opening 8 through which the tray 2 slides back and forth. The said opening 8 is entirely closed when the tray 2 is in its closed position, by means of a vertical tray-front 9 riveted to the extreme forward end of the tray. The said tray-front 9 is itself formed with a sight-opening 10 normally closed by 75 a door 11 formed at its lower end with a hinge 12 and furnished at its upper end with a handle 13. Upon its inner face the door 11 carries a glass 14 in which the flame will be reflected when the door is in its open position in which it is shown by broken lines in 80 Fig. 6.

The tray 2 forming the preheater-carrier proper carries an elongated metal bowl 15 formed at its upper edge with a horizontal 90 flange 16 supporting a sheet metal plate 17 corresponding in general form to the bowl and supporting an insulating-pad 18 cemented to it and made of asbestos or other suitable material. The plate 17 and pad 18 are respectively formed with large circular openings 19 and 20 concentric with the rounded rear end of the bowl 15. That portion of the bowl lying below these openings constitutes, as it were, the combustion-chamber 21 of the preheater. Centrally within the said combustion-chamber 21 I locate a removable burner 22 of any approved construction and furnished with a removable circular baffle-plate 23. The said burner 22 100 is mounted upon a burner-nozzle 24 in

which the liquid fuel is vaporized and from which the vapor is projected against the lower face of the baffle-plate 23 by which it is deflected into the burner-ports 25 from 5 which it rises to burn above the burner. The nozzle 24 is mounted upon the center of the burner-bridge 26 the ends of which are secured to threaded hubs 27 rising from the bottom of the bowl 15. Directly below the 10 burner 22 and concentric therewith, the bottom of the bowl 15 is formed with a circular flange 28 the parallel ends 29 of which are extended radially to meet the adjacent side wall of the bowl 15. The said flange 15 28 merges into the hubs 27 aforesaid and forms a shallow circular alcohol-cup 30 having a radial arm 31 over which the extreme inner end 32 of the fuel supply-pipe 33 extends. Within the alcohol-cup 30 rise two 20 segmental supporting webs 34, 34, which provide intermediate support for the bridge 26 as clearly shown in Fig. 6.

In order that the preheater as a whole may automatically accommodate itself to 25 the bottom 35 of the vertically movable food-container 36 when the same is in its heat-conserving or lowered position in which its ingress draft-passage 37 formed in the center of its bottom 35 is closed by 30 the preheater, the lower face of the bowl 15 is formed with a rounded bearing-lug 38 by which the entire bottom of the bowl is raised just enough above the upper face of the bottom of the tray 2 to permit the bowl 35 to rock upon the said bearing-lug 38 which permits the accommodation of the plane of the insulating-pad 18 to the plane of the bottom 35 of the food-container if any difference exists between these planes when the 40 food-container 36 descends into its lowered position. A rivet 39 passing through the bearing-lug 38 fastens the bowl 15 to the tray 2.

The tapering forward end of the bowl 15 45 forms in effect an air-passage 40 supplying abundant air to the combustion-chamber 21 and taking air from air-ports 42 and 43 respectively formed in the forward ends of the plate 17 and pad 18. In this connection 50 I wish it understood that I do not limit myself to the use in the bowl 15 of the burner of the particular construction described since other forms of burners might answer the purpose.

The burner, whatever its specific construction, has liquid fuel supplied to it 55 through the pipe 33 which extends forward over the bottom of the tray 2, the pipe being given sufficient downward pitch from its inner arm 32 to its outer end to insure its being drained into a liquid fuel-tank 44 suspended from the front end of the tray 2 by means of straps 45 the upper ends of which are applied to the front-plate 9 of the tray. The outer end of the pipe 33

passes through the said front plate 9 of the tray and enters an elbow 46 upon the upper end of a vertical feed-pipe 47 mounted in the top of the tank 44 and extending nearly to the bottom thereof.

For forcing liquid fuel, such as kerosene or gasoline, from the tank 44 through the feed-pipe 46, the elbow 47 and the pipe 33 into the burner 22, I employ an air-pump 48 mounted in the top of the tank 44 at 75 one end thereof and furnished with a manually operable plunger 49.

As long as sufficient pressure of air is maintained within the tank 44, the fuel therein will be forced into the burner. To 80 cut off the supply of fuel to the burner, I employ an air-release valve comprising a valve-body 50 which is fastened to the bottom of the tray 2 close to the forward end of the preheater-bowl in position to be operated 85 by the bottom 35 of the food-container 36 when the same descends into its closed position. An air-pipe 51 leads forward from the valve-body 50 through the tray front 9 and is connected with an elbow 52 carried by a short nipple 53 mounted in the top of the tank 44 and opening into the air space thereof. The said air-escape valve is furnished with a hollow plunger 54 mounted in a threaded gland 55 screwed into the upper 95 end of the valve-body 50. At its upper end the plunger 54 is furnished with an abutment-head 56 and formed with a transverse air-outlet port 57. Near its lower end the said plunger 54 is formed with a transverse air-inlet port 58, while its extreme 100 lower end is closed by a threaded plug 59 mounting a cup-shaped valve 60 carrying a washer 61 which co-acts with a valve-seat 62 formed by the lower end of the gland 55. The projecting lower end of the plug 59 105 forms a support for the upper end of a helical spring 63 located in the bottom of the valve-body 50 and exerting a constant effort to lift the plunger into its elevated position 110 in which its air-inlet port is closed and in which the washer 61 in the cup-valve 60 is crowded against the valve-seat 62.

For maintaining the air-escape valve in its open position, I employ a spring-latch 64 115 depending from the abutment-head 56 and bent to form a cam-like locking-shoulder 65 co-acting with a locking-pin 66 extending between two parallel vertical guide-flanges 67 formed upon the body 50 and receiving the said spring-latch between them. The lower end of the latch 64 is bent to form a circular finger-piece 68. By reference to Fig. 10, it will be seen that when the plunger 54 is depressed to move the air-inlet port 58 into its open position, the locking-shoulder 65 will ride over the locking-pin 66 and be engaged with the lower face thereof so as to lock the air-escape valve in its open position, whereby the pressure in the fuel tank 44 120

will be reduced to that of the atmosphere, preventing also the pressure therein from being raised above the pressure of the atmosphere by the careless or ignorant operation 5 of the pump 48, until the finger-piece 68 has been grasped and the spring-latch 64 sprung outward to release the shoulder 65 from the pin 66 after which the spring 63 will assert itself to lift the plunger 54 and close its inlet 10 air-port 58.

To notify the user of the apparatus when sufficient air-pressure has been developed within the tank 44, I set a thin, slightly concavo-convex disk 69 into a circular opening 15 70 formed for its reception in the middle of the front wall of the tank. The said disk 69 is predetermined in size and thickness so that when the pressure in the tank 44 has been raised to a predetermined number of 20 pounds, the disk will snap outward with a report which notifies the user of the device to stop pumping. The disk 69 may now be ignored until the next time the tank 44 is to be charged with compressed air when pressure of the thumb upon the disk forces it to snap inward with a corresponding report. 25 The disk therefore constitutes an auditory air-pressure signal.

For filling the tank 44 with liquid fuel, I 30 provide a removable nipple or filler-cap 71 mounting a needle-valve 72 which may be operated for reducing the air pressure in the tank if too high.

To indicate to the person filling the tank 35 when the proper level has been reached, I employ a visual fluid-level indicator comprising a glass dome 73 having its lower edge formed with an outwardly turned flange 74 extending under a flange 75 turned 40 inward from the upper end of a threaded nipple 76 mounted in the top of the tank 44, furnished with a knurled edge 77 and receiving a fixed retaining-shell 78 bent inward at its upper end to form a flange 79 45 constituting a bearing for a gasket 80 upon which the flange 74 of the dome 73 rests, the shell 78 being crowded into the nipple 76 before being fixed in place therein until the flanges 74, 75 and 79, and the gasket 80 are 50 crowded together. From the lower end of the shell 78 I suspend a concentrically arranged cup 81 by means of a transverse bridge 82 formed at each end with a pair of arms 83, 84, bent in opposite directions 55 and providing for the attachment of the bridge at each end to the shell and to the cup. The said bridge 82 is formed with a central opening 85 for the reception and guidance of a vertically movable stem 86 60 furnished at its upper end with a ball-signal 87 and carrying at its lower end a float 88 and a ball-valve 89, the latter being located directly below said float and co-acting with a seat 90 formed in the bottom of the cup 81 65 which is also formed with a port 91 through

which the extreme lower end of the stem 86 projects and which permits the cup to both fill and discharge. Under this construction the ball-signal 87 does not gradually rise in the glass dome 73 as the fluid level in the 70 tank 44 gradually rises when the tank is being charged. On the contrary, the ball-signal 87 rises suddenly just as the maximum fluid level is reached. This result is accomplished by positioning the upper edge 75 of the cup 81 a trifle lower than the maximum fluid level so that just before the maximum fluid level is reached, the fluid will begin to flow into the cup 81 over the upper edge thereof. As soon as sufficient fluid has 80 thus entered the cup to raise the ball-valve 89 from its seat 90, the cup will fill both from the top and bottom, with the result of speedily lifting the float 88 and hence of throwing up the ball 87 into the top of the 85 dome 73, thus signaling to the person filling the tank that the maximum fluid level therein has been reached. As the fluid level in the tank recedes, the float 88 will correspondingly fall by the flowage of the fluid in the 90 cup out through the port 91 which will not be closed by the valve 90 until practically all of the fluid has been drained out of the cup.

The tray 2 is drawn out into its open position for lighting the preheater-burner 22 and pushed back into its closed position to register the preheater-burner with the ingress-draft passage 37 in the food-container 36, by means of a handle 92 the ends of 95 which pass under the straps 45. For supporting the outer end of the tray when the same is in its open position, I employ a removable support 93 made from a single piece of heavy wire the upper ends of which 100 are turned inward at a right angle for the purpose of being hooked into sockets 94 in the ends of the handle 92.

Having now described the movable pre-heater-carrier, the burner, the fuel-tank and 110 the several appurtenances thereof, I will describe the other features of the typical apparatus.

The double-walled vertically movable food-container 36 already in part described, is 115 provided at its lower end, as shown, with an annular insulating ring 95 which rests upon the insulating-pad 18 of the preheater when the food-container is in its closed or lowered position. At its upper end, the said food-container is provided with a double-walled cover 96 lined with insulating material and provided with handles 97 and swinging locking-clips 98. The said cover 96 is formed with a concentric egress draft-passage 99 automatically closed upon the descent of the food-container by means of a suitable valve 100 suspended from the outer end of a lever 101 mounted in a bracket 102 fastened to the top of the cover, the said 120 125 130

valve 100 being normally held in its elevated position by means of a spring 103 located under the lever at a point in front of its pivot 104. The rear end of the lever 101 projects beyond the rear edge of the cover into a loop 105 formed in the upper end of a valve-operating frame 106 the legs of which are passed downward into the rear portion of the casing 5 through the annular top-plate 107 thereof and fastened in place by means of a clamp 108 secured to the inner face of the rear wall of the said casing.

For holding the food-container 36 in spaced relation to the preheater during the heat-charging period, I employ spacing-mechanism consisting, as herein shown, of two vertically movable spacing or suspension-bars 109 located opposite each other and having their main portions set inward to form vertical guides 110 which assist in keeping the food-container centered. The said bars 109 are furnished at their upper and lower ends with slots 111 for the reception of guide-pins 112 extending inward from the opposite side walls of the casing 5. At their lower ends, the bars 109 are formed with horizontal suspension-arms 113 upon which the food-container 36 actually rests. The said bars 109 are elevated for lifting the food-container 36 by means of a lever system comprising a horizontally arranged yoke 114 extending forwardly in the casing 5 and having its respective arms connected by pins 115 to the lower ends of the bars 109 and formed with slots 116 receiving aligned studs 117 upon which the yoke itself swings. The bowed forward portion of the yoke is pivotally connected at its center with the lower end of a lifting-rod 118 extending upward through a perforation in the flat top or plate 107 of the casing 5. The said rod 118 carries a spacing-member 119 forming at its lower end a spacing-shoulder 120, and at its upper end a stop-shoulder 121. The projecting upper end of the rod 118 terminates in a handle or grip 122.

The food-container 36 is latched, as it were, in spaced relation to the preheater, by means of a bell-crank latch 123 (Figs. 2, 3 and 4) hung within the front of the casing 6 upon a stud 124 and having its lower end adapted to be inserted under the spacing-shoulder 120 of the spacing-member 119. The horizontal upper arm of the latch 45 terminates at its outer end in a depending lug 125 which rests upon a tripping-lever 126 hung by its inner end upon a stud 127 and entered at its opposite end into an automatic controlling or timing mechanism 128 which may be of any approved construction such as that shown in my co-pending application Serial No. 782,245, filed Aug. 23, 1912. A spring 129 connected with the lever 126, exerts a constant effort to lift it and so swing the latch 123 on its stud 124 for the release

of the rod 118, and hence of the suspension-yoke 114, whereby the food-container 36 is released or "fired" and allowed to descend by gravity into its heat-conserving position in which its annular insulating-plate 75 rests upon the insulating pad 18 of the preheater and whereby the preheater is made to act as a closure and seal for the ingress draft-passage 37 of the food-container 36. The said tripping-lever 126 is provided with a handle 130 projecting forward through a slot 131 formed in the front of the casing 5, in position to co-act with the handle 132 of a setting-lever 133 which is located in front of a graduated dial 134 applied to the front of the casing. The said lever 133 is formed in its upper end with a pointer 135 which sweeps over the said dial and is mounted upon the projecting forward end of an arbor 136 constituting a member of the automatic controlling mechanism. The said arbor in turn carries a timing-disk 137 (Fig. 3) having a radial timing-slot 138 which receives a timing-pin 139 carried by the said tripping-lever 126 as more fully described in my pending application referred to. By means of the setting-lever 133 the controlling mechanism 128 is set to at a predetermined time, release the tripping-lever 126 and permit the same to be lifted by the spring 129 for swinging the latch 123 on its stud 124 for releasing the rod 118, and hence the food-container 36.

To forestall, or, as it were, anticipate the action of the automatic controlling mechanism 128, as may sometimes be desired for one reason or another, I mount a forestalling-pin 140 in the lower arm of the latch 123 and extend the same forward through a slot 141 in the front of the casing 5. By manually moving the projecting forward end of this pin 140, the latch 123 may be swung at any time so as to release or "fire" the food-container 36 and permit the descent of the same into its heat-conserving position.

In using my improved cooking apparatus, the fuel tank 44 is filled through the nipple or cap 71 until the ball-signal 87 suddenly rises in the dome 73 to indicate that the maximum fluid level has been reached. The subsequent steps in the operation of the apparatus must now be taken in the following predetermined sequence which is necessary in its main features for the operation of the apparatus and for safety. In the first place, the timing device 128 is set according to the length of time it is desired to use the preheater. The food-container 36 is then lifted by the handle 122 into position to be suspended in spaced relation above the preheater by the action of the bell-crank lever 123 which will not function to suspend the container until after the timing device has been so set, the setting of the timing device being a condition precedent upon the opera-

tion of the spacing mechanism for suspending the container. The raising and suspension of the food-container, releases the pre-heater, and hence the preheater-carrier or tray which may now be drawn outward into its open position by means of its handle 92. Alcohol is now poured into the shallow cup 30 and ignited for heating the burner 22, the baffle-plate 23 and the inner end 32 of the fuel pipe 33 to the degree required for the vaporization of the liquid fuel. Just before the alcohol flame goes out, the air-release valve is manually closed (having been opened by the last preceding descent of the food-container 36 into its closed position) by pulling outward upon its finger-piece 68 which disengages the top of the shoulder 65 from the lower face of the pin 66 and permits the spring 63 to assert itself in raising the hollow plunger 54 into position to shut off its air-inlet port 58. After the air-release valve has been closed, a few strokes of the pump 48 will start the liquid fuel flowing through the pipe 33. By the time this modicum of fuel reaches the burner 22 it will be vaporized and lighted by the last flickerings of the alcohol. The signal disk 69 is now snapped inward by the thumb and the pump 48 is operated until the disk 69 pops out with a report and signals to stop pumping. It is necessary, as I may here explain, to light the fuel vapor as soon as it begins to generate, since otherwise it would continue to escape during the entire pumping operation and cool off the burner. The tray is now pushed back into its closed position to register the preheater-burner with the ingress draft-passage 37 in the lower end of the food-container which is now in its elevated position. The burner continues to burn until the automatic controlling mechanism operates to function the spacing-mechanism to release the food-container which then descends into its closed position at which time both its inlet passage 37 and its egress passage 99 are automatically closed and sealed and the burner extinguished. As the burner is being extinguished, the container 36 descends upon the air-escape valve which it depresses and locks in its open position, permitting the almost instantaneous escape of the compressed air in the fluid tank. As the compressed air escapes, any oil that remains in the burner or pipe 33 is sucked back into the fuel-tank so that there is no chance for the entrance of any smoke or odor into the food-container after the preheater is extinguished.

I claim:

1. In a cooking apparatus, the combination with a vertically movable food-container having ingress and egress draft-pas-
sages, of a preheater adapted to act as a clo-
sure for the said ingress draft-passage, one
of the said parts being movable with respect

to the other, spacing mechanism for holding the said movable part in spaced relation to the other part, means for automatically controlling the releasing function of the said spacing-mechanism, a fuel tank connected with the preheater, and an air-escape valve connected with the said tank and automatically opened by the movement of the said movable part to stop the feeding of fuel from the tank to the preheater.

75

2. In a cooking apparatus, the combination with a vertically movable food-container having ingress and egress draft-pas-
sages, of a preheater adapted to act as a clo-
sure for the said ingress draft-passage, spacing-mechanism for holding the food-con-
tainer above the preheater in spaced relation thereto, means for automatically controlling the function of the spacing-mechanism in re-
leasing the container which descends upon the preheater for the closing of its said in-
gress draft-passage, a fuel tank connected with the preheater, an air-pump for the fuel tank, and an air-escape valve connected with the tank and automatically opened by the de-
scent of the food-container to stop the feed-
ing of fuel from the tank to the preheater.

80

3. In a cooking apparatus, the combina-
tion with a vertically movable food-con-
tainer having ingress and egress draft-pas-
sages, of a preheater adapted to act as a
closure for the said ingress draft-passage,
one of the said parts being movable with re-
spect to the other, spacing-mechanism for
holding the said movable part in spaced re-
lation to the other part, means for automatic-
ally controlling the releasing function of
the said spacing-mechanism, a fuel tank
connected with the preheater, an air-pump
for the fuel tank, and an air-escape valve
connected with the said tank and automatic-
ally opened by the movement of the said
movable part to stop the feeding of fuel
from the tank to the preheater.

90

4. In a cooking apparatus, the combina-
tion with a vertically movable food-con-
tainer having ingress and egress draft-pas-
sages, of a preheater adapted to act as a
closure for the said ingress draft-passage,
one of the said parts being movable with re-
spect to the other, spacing-mechanism for
holding the said movable part in spaced re-
lation to the other part, means for automatic-
ally controlling the releasing function of
the said spacing-mechanism, a fuel-tank
connected with the preheater, an air-pump
for the fuel tank, an air-escape valve con-
nected with the said tank and automatic-
ally opened by the movement of the said
movable part to stop the feeding of fuel
from the tank to the preheater, and a visual fluid-
level indicator mounted in the tank.

100

5. In a cooking apparatus, the combina-
tion with a vertically movable food-con-
tainer having ingress and egress draft-pas-
sages, of a preheater adapted to act as a clo-
sure for the said ingress draft-passage, one
of the said parts being movable with respect

110

115

120

125

130

- sages, of a preheater adapted to act as a closure for the said ingress draft-passage, one of the said parts being movable with respect to the other, spacing-mechanism for holding the said movable part in spaced relation to the other part, means for automatically controlling the releasing function of the said spacing-mechanism, a fuel-tank connected with the preheater, an air-pump for the fuel-tank, an air-pressure signal, an air-escape valve connected with the said tank and automatically opened by the movement of the said movable part to stop the feeding of fuel from the tank to the preheater, and a visual fluid-level indicator mounted in the tank.
6. In a cooking apparatus, the combination with a vertically movable food-container having an ingress and an egress draft-passage, of a preheater forming a closure for the said ingress draft-passage, spacing-mechanism for holding the container in spaced relation above the preheater, means for automatically controlling the releasing function of the spacing-mechanism, a laterally movable tray upon which the preheater is mounted, and means applied to the outer end of the tray for supporting the same in its open position.
7. In a cooking apparatus, the combination with a vertically movable food-container having an ingress draft-passage and an egress draft-passage, of a preheater adapted to act as a closure for the said ingress draft-passage, a laterally movable tray upon which the preheater is mounted, a fuel-tank at the outer end of the said tray, an air-escape valve connected with the said tank and operated by the descent of the food-container for permitting the compressed air to escape from the fuel-tank and stopping the feeding of fuel from the tank to the preheater.
8. In a cooking apparatus, the combination with a vertically movable food-container formed at its lower end with an ingress draft-passage, of a preheater adapted to act as a closure for the said ingress draft-passage, spacing-mechanism for holding the food-container above the preheater in spaced relation thereto, means for automatically controlling the function of the spacing-mechanism in releasing the container, a laterally movable tray carrying the preheater, a fuel-tank at outer end of the said tray, an air-escape valve connected with the fuel-tank and automatically opened by the descent of the food-container, an air-pump, and a fluid-level indicator and an air-pressure signal connected with the said tank.
9. In a cooking apparatus, the combination with a vertically movable food-container formed at its lower end with an ingress draft-passage and at its upper end with an egress draft-passage, of a preheater
- adapted to act as a closure for the said ingress draft-passage, spacing-mechanism for holding the food-container above the preheater in spaced relation thereto, means for automatically controlling the function of the spacing-mechanism in releasing the container, means for supplying liquid fuel to the preheater under atmospheric pressure, and an air-escape valve adapted to be automatically opened and locked in its open position by the descent of the food-container.
10. In a cooking apparatus, the combination with a vertically movable food-container formed at its lower end with an ingress draft-passage and at its upper end with an egress draft-passage, of a preheater adapted to act as a closure for the said ingress draft-passage, spacing-mechanism for holding the food-container above the preheater in spaced relation thereto, means for automatically controlling the function of the spacing-mechanism in releasing the container, means for supplying liquid fuel under air-pressure to the preheater, and an air-escape valve for stopping the feeding of the liquid fuel, the said valve being automatically opened by the descent of the food-container the lifting of which into spaced relation to the preheater must precede the closing of the said air escape valve.
11. In a cooking apparatus, the combination with a vertically movable food-container formed at its lower end with an ingress draft-passage and at its upper end with an egress draft-passage, of a preheater acting as a closure for the said ingress draft-passage, spacing-mechanism for holding the food-container above the preheater in spaced relation thereto, means for automatically controlling the function of the spacing-mechanism in releasing the container, a laterally movable tray upon which the preheater is mounted, a fuel tank at the outer end of the said tray, an air-pump connected with the said tank, and an air-escape valve connected with the tank and mounted upon said tray in position to be automatically opened by the descent of the food container into its closed position.
12. In a cooking apparatus, the combination with a vertically movable food-container formed at its lower end with an ingress draft-passage and at its upper end with an egress draft-passage, of a preheater adapted to act as a closure for the said ingress draft-passage, spacing mechanism for holding the food-container above the preheater in spaced relation thereto, means for automatically controlling the function of the spacing-mechanism in releasing the container, a laterally movable tray upon which the preheater is mounted, a fuel tank at the outer end of the tray, a fuel pipe leading from the tank to the burner of the preheater, an air-pump connected with the tank,

an air-escape valve connected with the tank and mounted upon the tray in position to be opened by the descent of the food-container, and means for automatically locking the air pump in its open position, and the lifting of the food-container being a condition precedent to the manual unlocking and closing of the said valve.

In testimony whereof, I have signed this specification in the presence of two subscribing witnesses.

ROSS M. G. PHILLIPS.
